UNITED STATES PATENT OFFICE.

JOHN E. BELL, OF BROOKLYN, NEW YORK, ASSIGNOR TO COMBUSTION ENGINEERING CORPORATION, A CORPORATION OF NEW YORK.

APPARATUS FOR BURNING FUEL.

Application filed September 16, 1922. Serial No. 588,564.

This application relates to an apparatus for burning fuels and it is especially useful in connection with stationary boilers burning pulverized fuel.

5 One of the primary objects of my invention is to protect the vertical walls of the furnace from erosion.

Another object of the invention has to do with the protection of the walls (and also the 10 bottom) and the prevention of formation of slag without uselessly lowering furnace temperatures.

Still another object of the invention is the 15 provision of a furnace in which steam is very efficiently generated.

More specifically stated, my invention has to do with the provision of an improved arrangement of cooling screens for furnace combustion chambers.

20 The foregoing, together with such other objects as may hereinafter appear, or are incident to my invention, I obtain by means of a construction which I have illustrated in preferred form in the accompanying drawings, wherein:

Fig. 1 is a section through a stationary boiler and combustion chamber therefor embodying my improvements; Fig. 2 is a front elevation of Fig. 1, Fig. 1 being taken on the line 1—1 of Fig. 2; Fig. 3 is a section taken on the line 3—3 of Fig. 1; and Fig. 4 is a section taken on the line 4—4 of Fig. 1.

The boiler is preferably of the type having a drum 7 connected by pipes 8 to a downcomer header 9 from which tubes 10 lead to an upcomer header 11 which in turn is connected with the drum 7 by means of tubes or pipes 12. The tubes of the boiler extend over the outlet opening 13 in the upper part 40 of the combustion chamber A.

45 The pulverized coal or a mixture of pulverized coal and air is admitted into an upper part of the combustion chamber by means of one or more burners B located so as to discharge the fuel in a downward direction adjacent the front wall 14 of the combustion chamber. The fuel and flame stream, under the action of the draft, take a U-shaped course through the combustion chamber toward the 50 outlet 13, the size of the combustion chamber being such that combustion is completed therein.

About ten percent of the air needed for combustion is supplied through the burner mechanism and the balance of the air re-

quired for combustion is supplied through the auxiliary air inlets 15, of which there are a battery in the front wall 14, and through the inlets 16 located in the side walls of the combustion chamber adjacent the front wall 60 and through which air is induced into the chamber from the channel 17 in the side walls. The air induced through the inlets 16 is thus preheated and the side walls are cooled by the absorption of heat, while the air induced through the inlets 15 is of atmospheric temperature.

Since the coal is delivered in a downward direction, usually with carrying air, it enters at a velocity greater than the velocity of the 70 air induced by the draft through the inlets 15 and 16 and the incoming coal is, therefore, projected through or past slower moving bodies of air. This sets up some measure of eddying very promptly, thus ensuring relatively prompt ignition, and in addition the particles of fuel are continually being brought into contact with fresh air and the gases emanating from the particles are stripped therefrom exposing fresh surfaces. Further- 75 80

more, by virtue of the difference in temperature and also by virtue of the force effect of the downcoming stream or streams of coal, a portion of the air admitted through the inlets, particularly the lower inlets, takes a 85 stream-line course bordering the fuel and flame stream on the convex side thereof, providing a body of air into which the heavier gravitating particles of fuel will find their way and there be supplied with oxygen needed 90 for their combustion. The inlets may be suitably damper controlled if desired.

In the bottom of the combustion chamber I provide a water screen C composed of a plurality of rearwardly and upwardly inclined 95 tubes 17, the forward ends of which are connected to a header 18 located in advance of the front wall 14, the rear ends of the tubes being connected to a header 19 just back of the bridge wall 20. The header 18 is connected by a plurality of pipes 21 to individual anchored boxes 22 which in turn are connected by a plurality of pipes 23 to the downcomer header 9 through the medium of the header 24. The number of pipes 21 and 23 may be varied as 100 105 the particular installation requires. The manner in which the header 19 is connected into the circulation of the boiler will be later described.

The tubes 17 are spaced sufficiently far 110

apart to permit the refuse matter gravitating out of the fuel and flame stream to deposit on the floor 25 of the combustion chamber, the function of the screen being to absorb radiant heat from the deposit so as to maintain the temperature thereof below the fusion or slagging point in order that the deposit may remain in the form of an ash which is readily removable through the cleanout doors. The screen is also utilized for generating steam as it will be apparent that the water circulating through the screen will be subject to great heat.

Immediately in front of the bridge wall 20 is another water screen D, composed of a plurality of substantially vertically disposed pipes 26 connected at their lower ends with the header 19 and at their upper ends with the header 27, just to the rear of the bridge wall. The upper ends of the pipes 26 are bent and extend through the bridge wall for connection with such header. The header 27 is connected by a plurality of pipes 28 to the up-comer header 11, such pipes 28 also extending along the inner face of the upper portion 20' of the bridge wall, so that such pipes are also in the nature of a screen, serving to absorb radiant heat from the bridge wall and from the deposit thereon.

30 The side walls 29 of the combustion chamber are also provided with cooling screens E, such screens comprising a plurality of pipes 29^a, the lower ends of which are bent and passed through the side walls for connection with a header 30, the header 30 being in turn connected to the header 18 by means of the pipes 31. The upper ends of the pipes 29^a are similarly bent so as to extend through the side wall for connection with a header 32, such header being connected to the header 34 by means of pipes 33. The header 34 is connected to drum 7 by means of pipes 35.

It will be seen from the foregoing that the screen C, the screen E, the screen D and the pipes 28 are all connected in the circulation of the boiler. The function of the screens D and E and pipes 28 is to protect the vertical walls of the combustion chamber against erosion by absorbing radiant heat from the deposit so that such deposit will not be turned to slag. The deposit is generally in the form of "whiskers" which will break off by reason of their own weight if fusion is prevented. Where slag is formed on the side walls, the surface of the brick is washed away as the slag runs down, which, of course, involves maintenance charges and other losses incident to shut-down, etc. There may be some deposit on the tubes of the various screens, but this is relatively slight because of the small area and rounded surfaces presented. The deposit builds up slightly and then runs off, the drippings being in the form of nodules which are solidified or cooled by the action of the screens, remaining in nodule form so that

their removal presents no difficulty. The screens D and E are located in the zone of highest temperature and are, therefore, subject to the greatest heat and they add very materially to the efficiency of the boiler in 70 the generation of steam, the contents of the boiler being turned over very rapidly. The chamber A, is, therefore, in effect, a combined combustion and boiler space in which provision is made for the abstraction of heat at 75 zones of very high temperature.

In this connection, it will be noted that while the effect of the screens is, of course, to lower temperature, nevertheless, this is brought about by the useful absorption of 80 heat and is, therefore, efficient. Heretofore, in some installations it has been the practice to prevent slag formation by admitting excess quantities of air, i. e., a material excess over and above that which is required 85 for the combustion of the coal, but this results in a useless lowering of the furnace temperature and an increase in the volume of gases to be handled, a method of operation which imposed practical limitations on the 90 efficiency and CO₂ obtained. According to my invention, I preferably propose to admit only the amount of air that is necessary for securing combustion of the coal.

It will be observed that the screens D and E present practically no obstruction to the flow of the fuel and flame stream and they permit of the fuel being fed at a higher rate without danger of forceful impingement of the flame on the vertical walls because the 100 chilling effect of the tubes in the absorption of heat prevents or limits flame travel or rather flame spread laterally. The flames may occasionally lick the tubes or travel closely adjacent thereto just as in the case 105 with the tubes of the screens C. These latter tubes, while not presenting a physical barrier to the downward progress of the flame, nevertheless impose a practical limit to the downward travel thereof by virtue of their 110 absorption of heat. The tubes of the screens D and E and pipes 28 may function in less degree in this respect because of their closer proximity to the walls, but they, nevertheless, serve to limit or define the zone of combustion and measurably prevent contact of the flames on the walls.

The front wall is protected by virtue of the admission of air therethrough and through the inlets 16 which provide, as previously pointed out, a bordering stream of air on the convex side of the fuel and flame stream.

At least a portion of the air admitted through the inlet 16 is drawn along the surface of the side walls by the action of the draft and other forces so that it is ordinarily unnecessary to carry the screens E farther forward than indicated.

Generally speaking, therefore, the combus- 130

tion may be said to take place in a zone, the cross sectional dimensions of which are all less than the corresponding cross sectional dimensions of the combustion chamber, and 5 the vertical dimensions of which are less than the distance between the bottom of the combustion chamber 25 and the tubes 10. The boiler may thus be forced to a greater degree without the liability of forcible impingement upon refractories and the formation 10 of slag, combustion being still completed within the combustion chamber and no unconsumed products being carried into the tubes 10 of the boiler.

15 Other advantages will occur to those skilled in the art.

What I claim is:

1. In a furnace, a combustion chamber; a boiler having a downcomer and an upcomer 20 header; a water screen in the bottom of the chamber exposed to radiant heat and comprising tubes and a pair of headers exterior of the chamber with which the tubes are connected; means for connecting one of said 25 headers with the downcomer header; a second water screen along the bridge wall exposed to radiant heat and connected with the other of said headers; a header with which the tubes of the second screen are connected; 30 and a plurality of tubes exposed to radiant heat and extending along the bridge wall for connecting said last header with the upcomer header.

2. In combination, a furnace having a refractory combustion chamber provided with an outlet, a boiler subject to the outlet flow, a 35 row comprising a plurality of exposed upright highly heat absorbing tubes of the boiler on the rear wall and on a portion of each side wall and defining a material portion of the combustion space, said refractories defining other portions of the combustion space and means for admitting finely divided fuel to the combustion chamber adjacent 45 the portions defined by the refractories.

3. In combination, a finely divided fuel burning boiler furnace, means for admitting the fuel to be burned in suspension therein, a 50 row of tubes below and marginal of the zone of combustion and inclined somewhat from the horizontal, a header at the upper end of said tubes, a row comprising a multiplicity of exposed upright tubes extending over an upright wall of the furnace and directly connected to the said header, downcomer means not exposed to high heat leading from the boiler to the lower end of said first mentioned row of tubes, and means connecting the upper end of the row of upright tubes to the boiler. 55

60 4. In combination, in a finely divided fuel burning boiler furnace, a refractory combustion chamber provided with an outlet, a boiler subject to the outlet flow, burner means at the front wall of the chamber, a row com-

prising a multiplicity of relatively closely spaced exposed tubes extending over and substantially proximate to another upright wall of said chamber in advance of the boiler and removed from the point of fuel admission and located in a region adjacent the zone wherein the fuel and flame stream has its greatest expansion and highest temperature, and means for connecting the said tubes into the circulation of the boiler.

5. In combination, in a finely divided fuel burning furnace, a combustion chamber, means for admitting fuel to be burned in space therein, a boiler served thereby, a row comprising a multiplicity of relatively closely spaced inclined, highly heat absorbing tubes in the bottom of the chamber, a header for the upper end of the tubes of said row, a row comprising a multiplicity of relatively closely spaced, highly heat absorbing tubes in said chamber at a side thereof and rising from said header, the upper end of said last mentioned tubes being connected with a boiler for circulation purposes, and downcomer means from the boiler not exposed to high heat for supplying said first mentioned inclined tubes with water.

6. The combination of a pulverized fuel furnace with a superjacent watertube boiler, spaced watertubes in the furnace combustion chamber to obviate slagging, and circulatory connections from the boiler to the ends of said tubes, including an upflow pipe, a header at the upper end of said pipe, and horizontal return tubes extending from said header to the downflow end of the boiler.

7. The combination with a furnace and tubular boiler having a steam and water drum, of means for introducing fuel to be burned in space in the furnace, a cooling screen comprising a row of spaced tubes within the furnace, a downcomer for the screen connected to water space of the boiler, a header for the screen, an upcomer from said header, a second header, connected to said upcomer, and a plurality of tubes leading from said second header to the drum.

8. In combination with a steam boiler having a steam and water drum, a furnace chamber, a plurality of water tubes arranged in said chamber so as to receive heat therefrom, 115 downtake and uptake connections between said tubes and boiler, said uptake connection comprising a conduit outside the boiler setting, and a plurality of vertically spaced tubular elements lying in more than one vertical plane connecting said conduit and said drum, at least the topmost one of said elements entering the drum above the normal water level therein.

In testimony whereof, I have hereunto signed my name.

JOHN E. BELL.
